(57) **CLAIM**

The ornamental design for spectacles, as shown and described.

DESCRIPTION

FIG. 1 is a front perspective of spectacles, showing my new design;

FIG. 2 is a front view thereof;

FIG. 3 is a rear view thereof;

FIG. 4 is a side view thereof;

FIG. 5 is a side view thereof, opposite that of FIG. 4;

FIG. 6 is a top view thereof;

FIG. 7 is a bottom view thereof; and,

FIG. 8 is an enlarged detail front perspective view taken from portion 8 in FIG. 1.

The broken lines shown in the drawings illustrate portions of the spectacles that form no part of the claimed design. The dash-dot broken line indicates cutoff boundaries for enlarged detail portion views and form no part of the claim.
